METAL STOCK FEEDER MECHANISM

Bernard Nadel, Riverside, R. I.

Application August 24, 1953, Serial No. 376,194

1 Claim. (Cl. 271—2.5)

The present invention relates to metal stamping and has particular reference to sheet stock feeding.

The principal object of the invention is to provide a feeding mechanism which feeds sheet stock continuously forwardly in intermittent steps.

Another object of the invention is to provide a feeding mechanism which advances sheet stock intermittently without drag.

A further object of the invention is to provide an intermittent feeding mechanism which does not mar the surface of sheet stock.

An additional object of the invention is to provide a feeding mechanism having a reciprocating and a stationary stock gripping device which cooperates to alternately pull the stock forwardly on forward movement of the reciprocating gripping device and hold the stock stationary on rearward movement of the reciprocating device.

In one aspect of the invention, the fixed and reciprocable feeding members each have a stock gripping device, the feeding members being movable relative to each other by a suitable means. Each of the stock gripping devices has a channel extending therethrough for receiving the strip stock to be fed, the channel having a transverse slot or wedge-shaped opening for receiving gripping rollers. The slot has opposed substantially planar roller guide surfaces inclined toward each other, one surface being above or on one side of the channel and the other below or on the other side of the channel. Resilient means, which may be spring means, urge the rollers toward each other so as to grip and center the stock when the rollers are moved convergingly toward each other.

With the above and other objects and advantageous features in view, the invention consists of a novel arrangement of parts more fully disclosed in the detailed description following, in conjunction with the accompanying drawings, and more specifically defined in the claim appended thereto.

In the drawings,

Fig. 1 is a front elevation of an illustrative feed mechanism embodying the invention, the pitman rod being partially broken away;

Fig. 2 is a side view of Fig. 1, the parts being in initial feeding position, the end feeding position being indicated in dotted lines;

Fig. 3 is a view of the rear plate of the feeding members;

Fig. 4 is a view of the front plate of the feeding members;

Fig. 5 is an enlarged vertical longitudinal section through the feeding members on the line 5—5 of Fig. 1, the parts being in initial feeding position;

Fig. 6 is a view similar to Fig. 5, the parts being in end feeding position;

Fig. 7 is a sectional detail on the line 7—7 of Fig. 6;

Fig. 8 is a sectional detail on the line 8—8 of Fig. 7; and

2

Fig. 9 is a perspective view of a feeding member block.

It has been found desirable to provide a sheet stock feeding mechanism which continuously advances the stock in desired selectively uniform increments of lengths without marring the surface thereof. To this end, I provide a base having a fixed member and a reciprocable movable member on which I mount two stock gripping devices, securely mounting one device in the fixed member and securely mounting the second device on the movable member in alignment with the first device. The gripping devices have through feed passageways which are in alignment and which have rollers seated in a wedge shaped opening positioned astride each passageway to receive strip stock therebetween. The rollers

slidably move within the wedge shaped opening towards and away from each other in response to the reciprocating movement of the movable member, whereby the strip stock is intermittently moved forward by the action of the rollers within the gripping device on the movable member and is held against rearward movement by the rollers within the gripping device on the fixed member.

Referring to the drawings, the novel feeding mechanism 10 includes a fixed feeding member 11 and a reciprocable feeding member 12, the reciprocable feeding member including parts for gripping a length of sheet stock and moving it forwardly when the reciprocable feeding member moves forwardly and for releasing its grip when the reciprocable feeding member moves rearwardly, the fixed feeding member including parts which give to permit the forward movement of the sheet stock and which grip to prevent rearward movement of the sheet stock when the reciprocable feeding member moves rearwardly.

The fixed feeding member 11 includes an upper block 13 and a lower block 14 which are of generally rectangular form as shown in Fig. 9, with a transverse slot 15 having parallel sides 16, 17 and an inclined lower face 18, the upper surface of the block having a feed recess 19. Two bores 20, are provided in the rear face 21 of the block, the bores inclining as illustrated in alignment with the inclination of the lower face 18, and terminating in reduced axial passages 22, whereby a plunger 23 may be mounted in each bore. The plunger 23 has a central disk portion 24, slidably positioned in its bore 20, an axial pin 25 extending rearwardly through the passage 22, and an axial stem 26 adapted to receive a compression spring 27, the end of the bore being closed by a lock stud 28 threaded or otherwise secured therein. A transverse roller 29 is positioned in slot 15, to be contacted and resiliently urged forward by the axial pins 25.

The blocks 13 and 14, after assembly of their plungers, springs and rollers, are secured together by a rear plate 30, see Fig. 3, which is attached thereto by screws or the like 31, and which has a transverse feed opening 32; the feed recesses 19 cooperating to provide a centrally positioned feed channel 33, see Fig. 4. The upper block 13 is similar to the lower block, with a similar roller 34 seated in a transverse slot 35, the upper face 36 of which is inclined as illustrated, and similar spring pressed plungers 37 and springs 38 seated in inclined bores 39.

The fixed feeding member 11 (Figs. 2, 5) is mounted in the vertical plate 40 of an angle support 41, the lower portion thereof providing a base 42 for mounting on a suitable table or the like. An angle shelf 43 has a feed shelf 44 with a lower flange secured to the base 42, the shelf 44 extending outwardly as illustrated and having a transverse slot 45 in which two roller guide elements 46 are adjustably mounted.

The reciprocable feeding member 12 is preferably of similar construction to the fixed feeding member 11, with an upper block 47 (Fig. 6), a lower block 48, an end

plate 49, rollers 51, 52 seated in transverse slots 50 having inclined upper and lower faces 53, 54 and spring pressed plungers 55, 56 (Fig. 5). The reciprocable feeding member 12 is mounted in a vertical plate 57, see Fig. 2, which has spaced upper guide passages 58 (Fig. 2) for slidably reciprocating on forwardly extending slide shafts 59 fixed to the vertical plate 40 of the angle support 41, the outer ends of the shafts 59 having stop disks 60 press fitted thereon.

Referring now to Figs. 2 and 6, an adjustment screw 61 is mounted to extend through the vertical plate 40 and the shelf 43, for engaging a stud 62 mounted in the rear face of the lower block 48 of the reciprocable feeding member, a second adjustment screw 63 being mounted in a rear bar 64 secured to the base 42 for contact with a stud 65 mounted in the forward face of the lower block 48, the screws 61 and 63 being set to provide end stops for the reciprocable feeding member.

The mechanism for reciprocating the reciprocable feeding member is shown in Figs. 1 and 2. The vertical plate 40 and the vertical plate 57 respectively have yoke members 64, 64A with cross shafts 66, 67 for pivotally receiving the lower ends of two toggle links 68, 69 which are pivotally connected at their upper ends to the cross shaft 70 of a yoke 71 adjustably threaded on the lower end of a pitman 72. The upper end of the pitman 72 is threaded into the socket 73 of the outer ring 74 of a universal coupling 75 mounted on the adjustable cross slide 76 of a drive wheel 77.

The operation of the novel feeding mechanism may now be explained. Sheet stock which is fed into the feed channel passes between the transverse rollers of the fixed feeding element and the reciprocable feeding element, the rollers being resiliently urged into contact with the upper and lower surfaces of the sheet stock. The reciprocable feeding member being pulled forwardly, see Fig. 6, pulls the sheet stock forwardly as the transverse rollers move rearwardly to provide a firm grip on both sides of the sheet stock; the transverse rollers of the fixed feeding element shaft upwardly against spring tension to permit this forward movement of the sheet stock.

The forward movement and rearward movement of the reciprocable feeding mechanism are limited by the forward adjusting screw and the rear adjusting screw, the length of the pitman and the setting of the stop screws being initially set, after a preliminary slight over-running adjustment, to obtain the exact feed desired. The rear-

ward movement of the reciprocable feeding member releases the grip of its transverse rollers, whereas return shift of the sheet stock causes the transverse rollers of the fixed feeding member to move down and grip the sheet stock on both surfaces to stop rearward movement of the sheet stock.

Although I have disclosed a specific constructional feature of my invention, it is obvious that changes in the size, shape and arrangement of the parts may be made, 10 without departing from the spirit and the scope of the invention as defined in the claim appended thereto.

I claim:

A feeding arrangement including a fixed feeding member and a reciprocable feeding member, said members 15 each having gripping device means, means for reciprocating said reciprocable feeding member forwardly and backwardly with respect to said fixed feeding member, each of said gripping device means having a longitudinally extending channel therethrough, strip movable through said 20 channel, a transverse slot across said channel, said slot having opposed roller guide planar surfaces, said surfaces being inclined towards each other and being symmetrical relative to each other, one of said planar surfaces being above said channel and the other being below said channel, 25 separable movable rollers positioned above and below said channel within said slot and between which said strip can pass, and resilient means urging said movable rollers against said inclined surfaces and towards each other and said strip therebetween, movement of said 30 strip relative to said rollers in the direction of convergence of said surfaces relative to each other moving said rollers along said opposed planar surfaces and towards each other into gripping engagement with said strip, said strip being centered in said channel as said rollers move together, 35 and being released when said rollers move apart due to movement of said strip in the opposite direction relative to said member.
